Primary Examiner — Daniel J Domino*Assistant Examiner* — Samina Vieth(57) **CLAIM**

The ornamental design for a Wifi router fixed mount, as shown and described.

DESCRIPTION

FIG. 1 is a top, front and left side perspective view of a Wifi router fixed mount, showing my new design;

FIG. 2 is a bottom, rear and right side perspective view thereof;

FIG. 3 is a top, rear and left side perspective view thereof;

FIG. 4 is a rear and bottom perspective view thereof;

FIG. 5 is a bottom and left side perspective view thereof;

FIG. 6 is a front elevational view thereof;

FIG. 7 is a rear elevational view thereof;

FIG. 8 is a left side elevational view thereof;

FIG. 9 is a right side elevational view thereof;

FIG. 10 is a top plan view thereof;

FIG. 11 is a bottom plan view thereof;

FIG. 12 is an enlarged view of portion 12 in FIG. 1;

FIG. 13 is an enlarged view of portion 13 in FIG. 8; and,

FIG. 14 is an enlarged view of portion 14 in FIG. 11.

The unevenly dashed broken lines define the boundary of enlarged views and form no part of the claimed design.
